UNITED STATES PATENT OFFICE.

ROBERT S. CRITCHELL, OF OAK PARK, ILLINOIS.

FIRE-PROOF BUILDING.

SPECIFICATION forming part of Letters Patent No. 400,309, dated March 26, 1889.

Application filed February 21, 1887. Serial No. 228,388. (No model.)

To all whom it may concern:

Be it known that I, ROBERT S. CRITCHELL, a citizen of the United States, residing at Oak Park, in the county of Cook and State of Illinois, have invented new and useful Improvements in Fire-Proof Buildings, which I desire to protect by Letters Patent of the United States, and of which the following is a specification.

10 Heretofore in the construction of fire-proof buildings a difficulty which has been encountered has been that, no matter how thoroughly fire-proof the walls the walls and the doors in the walls, the latter are likely to be 15 left open, so that when combustion occurs on one side of the wall it may be communicated through the door to that part of the building situated upon the other side of the wall.

My invention has for one of its objects to 20 overcome this liability to the spread of fire, and to that end I propose to separate the combustible portions of the building by a fire-proof wall and form an intermediate vacant portion by two secondary walls, which form an 25 angular recesses or extensions, and locate doors at the rear ends of said recesses or extensions, so that these doors communicate, respectively, with the combustible portions of said building. With this construction, even if both the 30 doors or sets of doors are left open, fire passing through one of the doors will find nothing to feed upon in the vacant inclosed space, and therefore cannot reach the combustible portions of the building upon the other side 35 of the wall.

A still more serious difficulty in the construction of fire-proof buildings has been that the stairways in ordinary buildings are always open, permitting the rapid ascent from 40 one floor to another of the flames, thus spreading the fire rapidly through the building.

It is one of the principal objects of my present invention to obviate this liability in fire-proof buildings to the spread of fire, and 45 to this end I propose to separate the combustible portions of the building by a fire-proof partition and in part by an inclosed portion provided by fire-proof walls, and locate the elevators and stairway or the like in 50 the rear part of said inclosed portion for communicating between the several floors of the building, and locate recesses or extensions in

the front part of said inclosed portion provided with doors opening into the combustible portions. This construction has the further incidental advantage that in case of fire the means of ascent for firemen and inmates are protected from destruction and from being rendered impassable by heat. 55

My invention further consists in certain details of construction incidental to and adapted for the general features outlined above. 60

In the drawings forming a part of this specification and annexed hereto, Figure 1 is a front elevation of a building in which my improvement has been introduced, a part of the front wall of the same being broken away to show the interior construction. Fig. 2 is a plan of the same, taken in cross-section on the line 2 2, Fig. 1. 65

The fire-proof wall A divides the building into the two parts referred to above, and branching from this main wall are two secondary fire-proof walls, B and C, connecting the main wall A with one of the outer walls 70 of the building, and inclosing between them and the outer wall the vacant space G, in which are located the stairway D, the freight-elevator E, and the passenger - elevator F. The only means of communication between 75 the inclosed space G and the other parts of the building are through the doors H and I, located in recesses or extensions of the inclosed space, said recesses or extensions being designated by the letters J and K. The 80 outer wall of this inclosed space is formed in part of window-glass, L, and sheet-iron, M, the latter being placed near the floor of each story and the former between it and the ceiling, the object being to have near the floor in each 85 case a material not easily damaged by merchandise handled in the elevator passage-way, and to so locate the window-glass as to most effectually light the interior space, and also to have an exterior wall for the passage-way which can be easily broken and penetrated by firemen. 90

This glass-and-iron structure may extend over the entire front of the inclosed space G, instead of across its central portion merely, as shown in the drawings, and this is indeed probably the preferable construction, for the reason that it is desirable to have as wide a space as possible adapted 95 for easy entrance into the building, and it is 100

also desirable that the windows should have considerable expanse.

The construction being as described, it will be seen that if one apartment of the building takes fire the flames cannot reach the other apartment through the doors I and II without traversing the entire space between them, and as this space is free from combustible material, and there are no other passage-ways between the two parts of the building, the one part is practically cut off from the other as regards fire.

The stairways and elevators are preferably constructed of metal. Nevertheless, the peculiar form of the space G, it being provided with recesses or extensions K, through which the heat and flames must pass to reach the elevators and stairway, would afford protection for the latter, even if they were made of combustible materials. These recesses or extensions should be of the minimum width required for the communicating doors, which in most commercial buildings would probably be about six feet, and a length equal to their width would probably be sufficient to render them effectual, although in the drawings they are represented as considerably longer than their width. Stand-pipes O, for carrying water to the top of the building, are located, as shown, within the space G.

It will be understood that the several features of my invention, hereinbefore described, are to a certain extent independent of each other, and I desire to protect them separately, as well as in combination. Thus the inclosed space G would be to a considerable extent effectual were the doors placed in its walls without the recesses J and K, although the construction with the recesses is in my judgment superior to the construction without them. So, too, the inclosed space may be devoted exclusively to the purpose of preventing the passage of fire from one part of the building to the other, and the stairways and elevators may be elsewhere located. So, too, this passage-way might be used in the interior of the building, or, if adjoining an exterior wall, the peculiar formation of that wall, herein described, consisting of glass and sheet-iron, might be dispensed with without altogether giving up the advantages of my construction. It will also be seen that any number of these spaces and communicating doors may be applied to a single building in different parts thereof, the number required being dependent upon the number of fire-proof walls and the uses to which the building is to be put.

It will also be observed that my invention

would have utility were it confined merely to the features of the recesses J and K; for supposing that the two parts of the building were separated from each other by the walls A and B alone, the space G being entirely dispensed with, even then the flames would have to pass from the door I entirely through the recess K before finding any material to feed upon, and if this recess were of sufficient length, passage of the flames through it would be practically impossible. When the vacant space G is merely used as a protection for the elevators and stairways, there may be but a single door or set of doors, I, into the vacant space, instead of the two doors shown; or the number of such doors may be increased, as desired.

Having thus described my invention, what I claim, and desire to protect by Letters Patent, is—

1. A building provided with combustible portions separated by a fire-proof wall, an intermediate vacant portion formed by two secondary fire-proof walls, and doors located at the rear end of angular recesses or extensions formed by said secondary walls, the doors communicating, respectively, with the said combustible portions, substantially as described.

2. A building provided with a fire-proof partition-wall, A, secondary fire-proof walls C and B, connecting said partition-wall with the exterior wall of the building and forming recesses J and K therewith, and doors H and I, located in said recesses J and K and opening, respectively, into the separated main portions of the building, substantially as described.

3. In a building, the combination, with combustible portions separated from each other in part by a fire-proof partition and in part by an inclosed portion provided with fire-proof walls, of elevators, stairways, or the like located in the rear part of said inclosed portion for communication between the several floors of the building, and recesses or extensions in the front part of said inclosed portion provided with doors opening into the combustible portions, substantially as described.

4. In a fire-proof building, the combination of fire-proof wall A, walls C and B, connecting said wall A with one of the exterior walls of the building, sheet-metal plates M, window-glass L, and communicating doors H I, substantially as and for the purpose set forth.

ROBERT S. CRITCHELL.
